(57) CLAIM

The ornamental design for a tumbler, as shown and described.

DESCRIPTION

FIG. 1 is a top perspective view of a tumbler of the present invention;

FIG. 2 is a front view of the tumbler of FIG. 1;

FIG. 3 is a back view of the tumbler of FIG. 1;

FIG. 4 is a top view of the tumbler of FIG. 1;

FIG. 5 is a bottom view of the tumbler of FIG. 1;

FIG. 6 is a left view of the tumbler of FIG. 1;

FIG. 7 is a right view of the tumbler of FIG. 1; and,

FIG. 8 is a perspective view of the tumbler of FIG. 1 with a straw portion in an extended position.

The portions of the tumbler shown in the broken lines in FIGS. 4 and 8 form no part of the claimed design.

The portions of the tumbler shown within the broken lines in FIG. 5 form no part of the claimed design.
